[57] CLAIM

What is claimed is the ornamental design for a soccer player antenna-topper, as shown and described.

DESCRIPTION

FIG. 1 is a perspective view of a soccer player antenna-topper, showing my new design;

FIG. 2 is a front view thereof;

FIG. 3 is a back view thereof;

FIG. 4 is a left side view thereof;

FIG. 5 is a right side view thereof; and,

FIG. 6 is a top view thereof.

The surfaces of the article not shown in the drawing or described in the specification form no part of the claimed design.
